UNITED STATES PATENT OFFICE.

WILLIAM W. WALKER, OF CAMDEN, NEW JERSEY, ASSIGNOR, BY MESNE ASSIGNMENTS,
TO FOAMITE FIREFOAM COMPANY, OF NEW YORK, N. Y., A CORPORATION OF DELA-
WARE.

PROCESS OF AND APPARATUS FOR EXTINGUISHING FIRE.

1,299,272.

Specification of Letters Patent.

Patented Apr. 1, 1919.

Application filed December 29, 1916. Serial No. 139,444.

To all whom it may concern:

Be it known that I, WILLIAM W. WALKER, a citizen of the United States, residing at Camden, in the county of Camden and State of New Jersey, have invented certain new and useful Improvements in Processes of and Apparatus for Extinguishing Fire, of which the following is a specification.

This invention relates to a process of and apparatus for extinguishing fire.

The principal object of the invention is to extinguish fire by the process of conducting two separated and different solutions which are under pressure, from their source which may be an apparatus of a portable nature, such for instance as the one shown in my Patent No. 1,186,250, although the apparatus may be used in any other connection with any other source to allow the commixture of such solutions at a point in close proximity to the fire and at the same time to allow the commingling solutions to be projected and scattered under pressure at any and all points about the place of its employment so that a more effectual smothering or extinguishment of the fire can be accomplished.

Another object of the invention is to provide readily portable means in the nature of a nozzle, which first receives the solutions in their separate condition to be subsequently brought together therein and projected therefrom in the form of a stream. Means are also provided which include a flexible element to connect said nozzle with the source of supply of said solutions, the second mentioned means also including means for normally preventing the flow of the solutions in their separate condition to said nozzle which in accordance with this invention may be at a very remote point from the source of supply of the solutions so that a better extinguishing agent will result as well as permitting of its employment in a more efficacious manner.

Another object of the present invention is to provide a readily movable portable nozzle, which receives the solutions in their separate condition, the said nozzle including a valve for regulating the flow of the solutions, so that they will flow simultaneously and in proper quantities to a mixing chamber which forms a part of the nozzle, said nozzle also having a reducing chamber to thus cause the commingling solutions to be

projected at a higher velocity and to a greater distance. Reaction of the solutions occurring gradually as they leave the nozzle in the form of a stream through the air. Hence deterioration of the commixing solutions cannot occur, which is a great advantage; the gaseous foam forming at the fire with all of its inherent extinguishing qualities.

In the drawings:

Figure 1 is an elevation illustrating and merely representative of the apparatus connected to a source from which different foam-producing chemical solutions are drawn under pressure.

Fig. 2 is a plan view showing in section the means for normally preventing the flow of the solutions from their source to the nozzle, the means is in the nature of a two-port four-way valve and it is shown in open position.

Fig. 3 is a longitudinal horizontal sectional view of the nozzle taken on the line 3-3 in Fig. 1.

Fig. 4 is an end elevation of the nozzle.

Fig. 5 is a transverse sectional view taken on the line 5-5 in Fig. 3 and looking in the direction as indicated by the arrow.

Fig. 6 is a detail sectional view of the duplex hose.

Referring now to the drawings in detail, the numeral 1 designates a portion of a vessel or vessels which contains under pressure in a separate condition two solutions which when commixed, generate a gas non-supporting to combustion. One of the solutions or both, preferably one, contains an admixture, preferably a substance or material which when combined with the one solution operates to produce a blanketing or smothering foam when commixed with the other solution to prevent the mentioned generated gas from escaping into the atmospheric air in and during the employment of the solutions. Outlet pipes 2-2 conduct the solutions from the vessel or vessels to a standard four-way valve 3, which normally prevents the flow of the solutions through the flexible duplex hose 4 to the nozzle 5.

The nozzle 5 consists of a barrel 6 having inlet ducts 7 therein, which communicate with a valve chamber 8. Nipples 9 are formed on the end of the barrel 6 and in which the ducts 7 are continued. The duplex hose 4 connects the nozzle 5 with the

four-way valve 3 through said nipples 9. The wall 10 of the valve chamber 8 is provided with ports 11-11, which are in direct communication with the mixing chamber 12 of the barrel 6. The end of the barrel 6 having the mixing chamber 12 therein is externally screw threaded so as to accommodate the reducing section 13 of the nozzle so called because of its tapering nature. It will also be noticed that mixing chamber 12 is of a tapering nature, tapering as it does toward the reducing chamber 14; the reducing chamber being as it were, a continuation of the mixing chamber 12. It will also be noticed that the ducts 7 converge toward the valve chamber 8, the reason therefore will appear. Positioned in the valve chamber 8 for turning movement is a cone-shaped valve 15, having transverse passages 16-16 therein. Said passages when the valve 15 is turned are adapted to establish communication between the inlet ducts 7 and the mixing chamber 12. The valve 15 is held in place in the valve chamber 8 by a nut 17 and the valve is provided with apertured extensions 18 adapting them to receive a forked actuating handle 19. The handle 19 is provided with stop-members 20 which limit the movement of the valve to open or closed position.

The valve 15 when brought to its open position permits the flow of the solutions which as stated are under pressure, from the vessel 1, to the mixing chamber 12. The valve 3 at this time, of course, has been opened as shown in Fig. 2. The solutions are maintained in their separate condition from the time they leave the vessel until they reach the nozzle. The solutions find their way into the inlet ducts 7 of the barrel 6 and as best perceived in Fig. 3, the solutions will be caused to flow toward each other without sudden agitation to cause their commixture, the flow occurring rather smoothly into the reducing chamber 14.

As will be understood, the separate streams which enter chamber 12 are not delivered in such form as to provide for a complete admixture in such chamber, the latter not being of a capacity which will permit the expansion action produced during reaction of the component elements of the extinguishing medium. And since the cross sectional area of the flow path of the combined streams is further decreased in passing into and through the nozzle 18, it will be readily understood that complete admixture does not take place prior to the discharge of the composite stream from chamber 14.

This action is advantageous in that the production of the gaseous medium with its foam is retarded although the separate streams are brought together. This action not only delays the activity of the reactions which take place so as to permit at least a

portion of such reaction activity to take place after the discharge of the composite stream from the nozzle, but also permits the use of a nozzle in such way as to provide a sufficient velocity to the stream as to tend to preserve the stream form for a sufficient time after leaving the nozzle as will permit complete reaction effect to be had, so that the maximum effect is produced at the point of application of the medium and reducing the tendency of the admixed elements to become spent in traveling to such point of application. In fact, the completion of the foam is had some distance from the discharge end of the nozzle.

As will be readily understood, this method of delivering the stream is of advantage through the fact that not only is it possible to use a portable nozzle which can be moved quickly from point to point, but in addition the extinguishing medium can be applied to a fire of that type which will prevent a close approach thereto, the ability to complete the medium at a point spaced from and in advance of the discharge end of the nozzle providing special advantages in fighting fires of this type.

I do not wish to be understood to be limiting myself to the construction and arrangement of parts shown nor to a particular arrangement thereof as I am aware that changes and alterations may be resorted to without departing from the spirit of the invention or the scope of the appended claims.

What I claim is:

1. The herein described process for extinguishing fire wherein the extinguishing medium is formed from two normally-separated solutions which, when commixed, produce a foam-extinguishing compound, said process consisting in delivering the separated solutions under pressure to a nozzle-carried chamber having a length insufficient to produce complete commixture of the solutions, discharging the chamber contents from the nozzle in stream form and under pressure, completion of the commixture and of the reaction occurring during stream travel to the point of application.

2. In apparatus for extinguishing fires by an extinguishing compound of the foam-extinguishing type formed from a plurality of solutions and wherein the solutions are normally maintained separate and are brought together to permit chemical reaction to produce the compound, and in combination, a stream-discharging nozzle having a chamber, sources of solution supply, and independent conduits connecting said sources with the chamber for concurrently delivering the solutions to the chamber under pressure to unite the separately-delivered solutions into stream formation and place the solution components in general reacting re-

- lation, said nozzle chamber having a length and cross and longitudinal sections to permit free passage of the composite stream therethrough with the stream form and solution pressure maintained and with the time of passage insufficient to permit complete reaction commixture of the combined solutions in advance of reaching the nozzle discharge, said nozzle providing a stream discharge under pressure tending to maintain the stream form until the point of application is reached, whereby solution reaction will proceed during stream travel to such point to deliver stream components in foam-extinguishing condition.
3. In apparatus for extinguishing fires by an extinguishing compound of the foam-extinguishing type formed from a plurality of solutions and wherein the solutions are normally maintained separate and are brought together to permit chemical reaction to produce the compound, and in combination, a portable stream-discharging nozzle having a chamber, sources of solution supply, and independent conduits connecting said sources with the chamber for concurrently delivering the solutions to the chamber under pressure to unite the separately-delivered solutions into stream formation and place the solution components in general reacting relation, said nozzle including a member having a barrel section and a tubular reduced section, said barrel section having independent passageways connecting the conduits with said tubular section, valve mechanism for concurrently controlling said passageways, and a nozzle section carried by said tubular section, said tubular and nozzle sections combinedly forming the receiving chamber for the solutions, said chamber having a length and cross and longitudinal sections to permit free passage of the composite stream therethrough with the stream form and solution pressure maintained and with the time of passage insufficient to permit complete reaction commixture of the combined solutions in advance of reaching the nozzle discharge, said nozzle providing a stream discharge under pressure tending to maintain the stream form in reaching the point of application, whereby solution reaction will proceed during stream travel to such point to deliver stream components in foam-extinguishing condition.
5. The process of forming a fire-extinguishing medium of the foam extinguishing type, which consists in delivering the component elements of the medium, in the form of separate streams, to and passing them under pressure and in contact, through a chamber of insufficient capacity to permit complete admixture of component elements and production of foam, and delivering the combined streams from the chamber into space under pressure to produce a composite stream of sufficient velocity to be projected in stream form and to travel in such form a distance sufficient to permit completion of the medium to fire-extinguishing condition.
- In testimony whereof I affix my signature in the presence of two witnesses.
